INTERNAL COMBUSTION ENGINE

Sherman D. Irving, Youngstown, Ohio

Application June 22, 1940, Serial No. 341,916

3 Claims. (Cl. 123—63)

This invention relates to an internal combustion engine.

The principal object of this invention is to provide an internal combustion engine in which the horse-power to weight ratio has been greatly increased over other forms known to the art.

A further object of this invention is to provide an internal combustion engine so constructed as to be almost free from vibration when in operation.

A further object of this invention is to provide an internal combustion engine equipped with a novel valve arrangement designed to provide higher efficiency.

A further object is to provide an internal combustion engine having a plurality of cylinders, each of which is adapted to be fired at both its upper and lower ends, thus providing two power impulses per cylinder in place of the usual one.

A further object of this invention is to provide an internal combustion engine having a plurality of cylinders, in each of which there is positioned a piston and piston rod adapted to receive power impulses originating in either end of each of said cylinders.

A further object is to provide an internal combustion engine having slid able guide members on the piston rods adapted to hold the pistons in correct position within the cylinders.

A still further object of this invention is to provide an internal combustion engine having a novel cam shaft construction.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawings, wherein—

Figure 1 is an end view of the internal combustion engine with parts in cross section.

Figure 2 is a side elevation of the internal combustion engine with parts in cross section, said cross section taken on line B—B of Figure 1.

Figure 3 is a top plan view of the invention, with parts in cross section taken on lines C—C of Figure 2. Lines A—A on this figure indicate the approximate cross section shown in Figure 1.

Figure 4 is a view of the left face of a valve

actuating cam used in operating the valves in the invention. Figure 4a is a view of the cam shown in Figure 4 and Figure 4b is a view of the right face of the cam shown in Figures 4 and 4a.

5 Figure 5 is a schematic wiring diagram of the electrical circuit of the engine.

By referring to Figures 1 and 2 of the drawings, it will be seen that the invention comprises a crank case 1 having a block 2 positioned thereon. A secondary block 3 is positioned upon the block 2, and has positioned upon it in turn a head 4. The block 2 has formed upon it a secondary head 5. A plurality of cylinders 6 are positioned within the secondary block 3, and 10 have a plurality of glands 7 connecting them to a plurality of openings 8 formed within the block 2. A double headed piston 9 and a piston rod 10 attached thereto is positioned within each of the cylinders 6 so that each of the piston rods 10 extend downwardly through the glands 7 into the openings 8. At the lower end of each of the piston rods 10, there is positioned a slid able cross head 11, which in turn is provided with the usual wrist pin and connecting rod 12. The connecting rod 12 is attached through bearings, to a crank shaft 13. This crank shaft 13, the connecting rods 12, the cross heads 10, and the pistons 9 are all drilled for oil passage for lubrication purposes as indicated by the numeral 35 in Figure 1 of the drawings.

In Figure 1, on the left side of the engine, and between the head 4 and secondary head 5, there is positioned a piston valve assembly comprising 35 a plurality of piston valves 14a and 14b, valve operating rods 15, and valve operating arms 16, which in turn are attached to valve control rods 17 and 18, the valve control rod 17 being positioned within the hollow valve control rod 18. 40 These valve control rods, arms, and piston valves are drilled for oil passage for lubrication purposes.

By referring to the lower portion of Figure 1 it will be seen that these valve control rods 17 and 18 are actuated by means of a double faced cam 19, which is in turn carried upon a cam shaft 20. Referring to the upper portion of Figure 1, an intake manifold is indicated by numeral 21 and exhaust manifolds are indicated by numerals 22 and 23, it being obvious that the exhaust manifolds 22 and 23 are respective integral parts of the head 4 and the secondary head 5. Suitable water jacketing is also indicated by the numerals 24. In Figure 2, spark plugs are indicated by numerals 25, while the valve operating

arms 16 and valve rods 15 are shown separated by small tension springs 26. The intake ports are indicated by numeral 27 while the exhaust ports are indicated by numeral 28. In the schematic diagram in Figure 5 the numeral 29 indicates the distributor and the numerals 30 and 31 indicate the two cylinders of the engine, while 32 and 33 represent the pistons.

To accurately describe the operation of this engine, it is necessary to refer to the degrees of rotation of the crank shaft, in order to fully understand the timing and firing principles. While it is evident that the engine could have any desirable number of cylinders, we have shown a two cylinder engine and the description of its operating reads accordingly. Starting at 0° and firing at the top of one of the cylinders, the crank shaft has revolved 180° when the second cylinder fires at its top. The crank shaft then revolves 180° further and that same cylinder fires at its bottom position. The crank shaft revolves 180° further and the first cylinder fires at its bottom position. This firing order is shown in a schematic diagram in Figure 5. It will be evident that the dual construction of this engine permits a power impulse to be applied to the crank shaft at every 180° of its revolution. It is further evident that the firing is at all times directly against compression, thus greatly cushioning and evening the flow of power impulses. The piston valves of the engine are actuated by the double faced cam 19, and in Figure 1 these valves are shown in firing position for the top of the cylinder 6. Thus the piston valve 14a is shown closing the port into the top of the cylinder 6 while the piston valve 14b likewise closes the port into the bottom of the cylinder 6. When the piston 9 has moved downwardly, the double faced cam 19 revolves and changes the position of the piston valve 14a, so that the upper portion of the cylinder 6 may be cleared of exhaust gases and recharged on the subsequent downward movement of the piston 9.

It is evident that this invention possesses many advantages over the earlier development of the art, one of the most important of which is its greatly increased power out-put per pound of weight. Another distinct advantage is its relatively small size which is due to the dual utilization of each cylinder. A still further outstanding advantage is its almost vibrationless operation due to its rotary-like application of power impulses to the crank shaft. Its unique manifolding's most obvious advantage is the relatively short distance the vaporized fuel must travel to reach the firing point. In the construction of its heads this engine has apparent advantages in that the firing charge is compressed directly over the piston, thus eliminating pockets which normally collect carbon. The valve construction in piston form provides a clear port from the carburetor to the combustion chamber as it sets up no obstructions. The piston valve itself provides a pumping action which tends to pull the fuel charge into the firing chamber. This pumping action is caused by the piston valve travelling past the cylinder port so that when its action is reversed it tends to create a partial vacuum thus drawing the charge of fuel mixture after it. The same advantages are apparent in the similar construction of the exhaust valves. These valves are opened and closed in a shorter period of time than has heretofore been needed for this purpose. The valve opens in approximately 41 1/2° and stays open for 60° additional,

and then closes, thus operating much faster than the ordinary poppet or sleeve valve. A still further advantage of this engine is its inherent balance of parts. The weight on the crank shaft is equally balanced at all times, thus helping to reduce vibration.

What I claim is:

1. The combination of an internal combustion engine adapted to use a fuel mixture and having a plurality of cylinders, a piston positioned in each of said cylinders, said pistons actuated on the four cycle principle but obtaining dual action by closing both ends of the cylinders with suitable cylinder heads to form combustion chambers, piston rods for said pistons, together with cross heads positioned on the said piston rods and having connecting rods attached thereto adapted to absorb any side thrust thus holding pistons and piston rods in correct position, together with timing and valve arrangements to provide two explosions every 720° in any and every cylinder, said valve arrangement comprising a plurality of piston valve cylinders, valve seats in said valve cylinders, a plurality of piston valves positioned one in each cylinder, ports formed between the said combustion chambers and the said valve cylinders, the said ports positioned away from said valve seats thus permitting the piston valves to travel past the said ports so that their reverse action will form a suction in the portion of the valve cylinder adjacent to the combustion chambers, a set of valve control rods for each of the said piston valves, each set of the valve control rods comprising a hollow rod having a solid rod positioned therein and actuated at their lower ends by double faced cams in such manner as to open and close in 113° of rotation of the crank shaft of said engine, substantially as described.
2. The combination of an internal combustion engine adapted to use liquid fuel, and having a plurality of cylinders, a piston positioned in each of said cylinders, said pistons actuated on the four cycle principle but containing dual action by closing both ends of the cylinders with suitable cylinder heads to form combustion chambers, piston rods for said pistons, cross heads positioned on the said piston rods and having connecting rods attached thereto, a crank shaft to which said connecting rods are suitably attached, the cranks of said crank shaft being spaced equi-distant necessarily due to the firing order of the engine in order to balance the crank shaft, in combination with suitable timing and valve arrangements to provide two explosions every 720° in any and every cylinder, said valve arrangement comprising piston valves in piston valve cylinders on said engine, the said piston valves being adapted to travel past the cylinder ports so that their reverse action will start the motion of vaporized fuel into the combustion chamber by forming a suction in the portion of the valve chambers adjacent to the combustion chambers, the exhaust valves performing the same function in starting the removal of exhaust gases, a set of valve control rods for each of the said piston valves, each set of valve control rods comprising a hollow rod having a solid rod positioned therein and actuated at their lower ends by double faced cams in such manner as to open and close in 113° of rotation of the crank shaft of said engine.
3. An internal combustion engine adapted to use liquid fuel and having a plurality of cylinders, a piston positioned in each of said cyl-

inders, said pistons actuated on the four cycle principle but obtaining dual action by closing both ends of the cylinders with suitable cylinder heads to form combustion chambers, piston rods for said pistons, cross heads positioned on the said piston rods and having connecting rods attached thereto, a crank shaft to which said connecting rods are suitably attached, the cranks of said crank shaft being spaced equi-distant necessarily due to the firing order of the engine in order to balance the crank shaft, in combination with suitable timing and valve arrangements to provide two explosions every 720° in any and every cylinder, said valve arrangement comprising a plurality of piston valve cylinders, 15 valve seats in said valve cylinders, a plurality of

5 piston valves positioned one in each cylinder, ports formed between the said combustion chambers and the said valve cylinders, the said ports positioned away from said valve seats thus permitting the piston valves to travel past the said ports so that their reverse action will form a suction in the portion of the valve cylinder adjacent to the combustion chambers, a set of valve control rods for each of the said piston valves, 10 each set of valve control rods comprising a hollow rod having a solid rod positioned therein and actuated at their lower ends by double faced cams in such manner as to open and close in 113° of rotation of the crank shaft of said engine, substantially as described.

SHERMAN D. IRVING.
